UNITED STATES PATENT OFFICE.

FRANCESCO CATALANOTTO, OF BROOKLYN, NEW YORK.

HINGE-SETTER.

1,326,583.

Specification of Letters Patent. Patented Dec. 30, 1919.

Application filed January 2, 1919. Serial No. 269,217.

To all whom it may concern:

Be it known that I, FRANCESCO CATALANOTTO, a citizen of the United States, residing at Brooklyn, in the county of Kings, 5 State of New York, have invented certain new and useful Improvements in Hinge-Setters; and I do hereby declare the following to be a full, clear, and exact description of the invention, such as will enable others skilled in the art to which it 10 appertains to make and use the same.

This invention relates to gages and more particularly to mortising gages and has special relation to gages for use in forming 15 hinge mortises both in doors and door jambs.

A particular object of the present invention is the provision of a gage which may be set directly from a hinge leaf to correspond to the width, length and thickness of 20 the leaf, and which may then be applied to a door in such a way as to present guide edges to indicate the dimensions of the mortise to be cut.

Another object is to provide such a gage 25 which, with slight modifications of its arrangement, may be used in connection with a door jamb.

Another object is to provide a gage having the above stated characteristics, which 30 may be used upon doors and jambs of different dimensions.

In the drawings:

Figure 1 is a perspective view of the present invention applied to a door.

Fig. 2 is an elevational view, the door being shown in dotted lines, and a chisel being also shown in dotted lines, in two positions of use.

Fig. 3 is a section on line 3—3 of Fig. 1.

Fig. 4 is a section on line 4—4 of Fig. 2.

Fig. 5 is a detail perspective showing the mounting of the depth guide plate extension in the side plate.

Fig. 6 is a perspective view showing the jamb attachments which are used without the width guide bar.

Fig. 7 is a detail perspective showing one of the jamb attachments which is used with 50 the width guide bar.

Fig. 8 is a detail section on line 8—8 of Fig. 1.

Referring now to the drawings, the present invention comprises a plate 10 forming a depth gage, end gage members 11 and a width gage member 12.

The plate 10 includes a longitudinal finger 13 at one end and at one side, the plane edge 10' of the plate which includes this finger serving as a depth guide, as will be 60 later explained. This plate 10 has an inner flat door-engaging face 14, as indicated.

Disposed against the outer face of the plate 10, there is a side plate 15, adjustable longitudinally with respect to the plate 10, 65 and held thereto by clamping bolts 16 working in slots 17. By means of these bolts and their wing nuts 18, the two plates may be held at different points of their adjustment with respect to each other. 70

At its end opposite to that which overlaps the plate 10, the plate 15 carries a rib 19 on its inner face, the inner face of this rib lying in a plane with the face 14 of the plate 10, and formed through this rib, there 75 is a guide way 20 in which the finger 13 is slidably received, as shown in Fig. 5.

Spaced flanges 21 are carried by the outer ends of the plates 10 and 15 upon their outer faces, the inner surfaces of these 80 flanges being converged outwardly to form dove-tail slots 22. These slots receive correspondingly formed arms 23 carried by the end gage members 11, the arms being slidable in the slots, and longitudinal slots 23' 85 are formed in the arms 23, and receive bolts 24 carried by the plates 10 and 15, these bolts being provided with nuts 25 which may be operated to clamp the arms against movement, as will be understood. The slots 90 22 extend transversely of the plates 10 and 15, as shown.

The end gage members 11 include plates 26 which lie at right angles to the plate 10, and which project inwardly toward each 95 other, beyond the arms 23. These plates include portions spaced from and parallel with the edge face 10' of the plate 10, as shown, and these portions of the plates 26 are thickened, as shown at 27, the thickened 100 portions extending inwardly beyond the face 14 of the plate 10. There are thus formed relatively thin portions of these plates 26, which extend beyond the thickened portions, these relatively thin portions 105 being indicated at 28, and which lie in a plane at right angles to the plane of the plate 10 and parallel with the plane of the edge 10' of the latter.

Engaged against the inner faces of the 110 portions 28, is the width gage member 12. The member 12 is in the form of a bar, pro-

vided with longitudinal slots 30, through which are passed bolts 31, and these bolts are also passed through slots 32 formed in the plates 26. The slots 32 extend transversely of the plates 26, and thus the bar is adjustable transversely of these plates, while the members 11 which include the plates, are adjustable longitudinally of the bar 29, toward and away from each other.

10 The bolts 31 are provided with clamping nuts 33, which are operable to hold the bar and plates at different points of their mutual adjustments.

15 At their ends opposite to the arms 23, the members 11 carry arms 34 extending in the same direction as the arms 23 and parallel therewith, and as shown in the drawing, Fig. 1, these arms 34 are arranged for disposal at one side of a door, against the op-

20 posite side face of which the plate 10 is engaged. With the arms and plate so disposed, the portions of the members 11 between their arms will extend across the edge face of the door, as shown, and the inner faces of the thickened portions 27 of the plates 26 will engage against this edge face of the door.

25 The members 11 thus constitute yokes, the arms of which are engageable at opposite sides of a door, with the yoke bights, formed by the plates 26 extending across the door edge.

30 The bar which constitutes the width gage member 12, carries an inturned flange 35 arranged to engage the edge surface of the door when the parts are disposed as just described, the free edge of this flange lying in a plane with the inner faces of the portions 27 of the plates 26.

35 Clamping screws 36 are threaded through the free ends of the arms 34, and are operable to engage against the side face of the door, to hold the complete device thereto.

40 When it is desired to set the present gage for the cutting of a mortise for a particular hinge leaf, the end members 11 are first set so that the inner faces of their thickened portions 27 lie spaced from the surface 10' of the plate 10 to an extent equal to the depth of the hinge leaf. The side plate 15 is then set so that the edges of the plate 26 which constitute portions of the members 11 are spaced a distance equal to the length of the hinge leaf, and the member 12 is set 45 so that its inner face is spaced from the face 14 of the plate 10 a distance equal to the width of the hinge leaf. This adjustment of the complete structure may be accomplished by disposing the hinge leaf properly between the parts to be adjusted, and then moving the parts into contact with the leaf as will be understood.

45 After adjustment, the device is placed upon the door as shown in Fig. 1, when the area of the edge face of the door bounded

by the inner sides of the plates 26 and the inner face of the member 12 will indicate the lines upon which the cut is to be made for length and width of the mortise, while the surface 10' of the plate 10 will indicate the line on which the cut is to be made for the depth of the mortise. A chisel A may be used as indicated in Fig. 2 for making the cuts.

When the device is to be used on a door jamb, I employ the end members 40 shown in Fig. 7. These end members are identical with the members 11, except that the arms 34 are omitted, and they are substituted for the members 11. In this use, the device is held against the door jamb, and the wood of the latter is marked with a suitable scribe to indicate the lines on which the cuts are to be made.

Some door jambs, by reason of moldings or other ornamentation thereon, may not permit of the use of the members 40, because of the length thereof, and I therefore provide shorter members 42, illustrated in Fig. 6, which are unprovided with the slots 32. It will be understood, of course, that when these members are used, the member 12 is dispensed with and the width of the mortise is marked in the usual way. Even without the member 12, however, the use of my device assures the marking of the tops and bottoms of the mortises so that they extend at right angles to the side faces of the door, and thus proper positioning of the hinges is assured.

It will be seen from the drawings that the present device has been designed to prevent any rocking movement of the adjustable parts with respect to each other, so that all gaging surfaces will remain perfectly true at all times.

What is claimed is:

1. A hinge mortise gage comprising a plate having a longitudinal gaging edge, a plate lapped upon the first plate for longitudinal adjustment therealong, means for locking the plates in different relative positions, slotted members having gaging faces parallel with the gaging edge of the first plate and having angular arms, each of said first plates being provided with a transverse guideway in which one of said arms is slidably engaged for movement of the members to shift their gaging faces toward and away from the gaging edge of the first plate, means for locking the said members at different points of such movement, said members including portions extending laterally of the plate and having gaging edges directed inwardly longitudinally of the first plate, a gaging member lying in a plane at right angles to the plane of the first plate and parallel with the plane of the gaging end thereof, said member having longitudinal slots at right angles to and registering with

the slots of the first mentioned members and clamp bolts engaged in said slots.

2. A hinge mortise gage comprising yokes having arms adapted to be disposed at opposite sides of a door with the yoke bights extending across the edge face of the door, a depth gage plate adjustably connected with the corresponding arms of the yoke at one side of the latter and shiftable toward and away from the yoke bights and a width gage member adjustably connected with the yoke bights for movement transversely of

the edge of a door with which the device is engaged, said yokes being adjustable also with respect to both the depth and width 15 gage members toward and away from each other.

In testimony whereof, I affix my signature, in the presence of two witnesses.

FRANCESCO CATALANOTTO.
